REGENERATIVE TURBINE PUMP

James O. McMillan, Wichita, Kans.

Application April 9, 1935, Serial No. 15,486

1 Claim. (Cl. 103—96)

This invention relates to pumps and more particularly to regenerative pumps and is a construction capable of pumping a mixture of water and air at the same time to as high a pressure 5 head with one impeller as will the commonly known multiple stage centrifugal pump. It is of the type having a casing provided with an inlet opening and outlet opening for receiving and discharging either liquid or liquid and air by 10 the action of a rotor of the single cone or double cone type with a multiplicity of enclosed vanes leaning in the direction of rotation, impinging against the free liquid in the channels of the pump and carrying the fluid therein with 15 it.

Operation of the pump is aided by kinetic energy, centrifugal force and tangential force, the combined action thereof resulting in a helical or spiral course or travel of the fluid to cause a 20 regenerative action or repeated impulses imparted to the particles of fluid as it travels through the channels.

One object of this invention is to improve this type of pump as to structure, efficiency and volume based on the discovery that if the raceways are properly curved and placed at right angles 25 to the axis and at an angle to the rotor, the helical path taken by the fluid and the pressure head will be increased.

A second object of my invention is to provide 30 a double cone or triangular rotor having two channels sealed one from the other to increase the volume, to balance the rotor load, and to prevent the impeller from becoming air bound 35 by providing such a rotor that one side may pump liquid and the other side may pump air.

A third object is to provide in a pump of the 40 general character stated, a chamber in which the liquid and air are separated and in which the liquid, or a portion of it, is revolved in the direction opposite to rotation of the rotor and the travelling fluid in the channels, and to return a portion of the water into the rotor chamber to 45 maintain a seal.

Another object of the invention is to provide 45 an impeller in which the channels and vanes are positioned at zones remote to the axis and have means for adjustment and increasing the capacity.

A further object is to provide an impeller in 50 which the vanes lean in the direction of rotation and are otherwise angular to cause the fluid to travel in a more pronounced spiral path to increase the pressure head. This construction

makes it possible to cast or die cast the impeller of bronze or other similar material.

Additionally, I aim to provide an impeller preferably having two raceways with means for adjustment while the pump is in operation to compensate for wear, to provide means for adjustment to take up wear in the raceways independently of the impeller, to provide such a pump with interchangeable and renewable raceway liners in which the fluid raceways are sealed one 10 from the other, and to provide a pump of this type in which one of the passageways may be used for low pressure and the other for high pressure to make a two stage pump for high pressure duty.

Various additional objects and advantages will 15 become apparent from a consideration of the description following taken in connection with accompanying drawings illustrating an operative embodiment.

In said drawings:

Figure 1 is a substantially central, longitudinal 20 sectional view through one form of pump according to my invention;

Figure 2 is a vertical, substantially central cross sectional view through said pump;

Figure 3 is a fragmentary side elevation of the 25 impeller;

Figure 4 is a cross sectional view taken on the line 4—4 of Figure 3;

Figure 5 is a detail view of the combination 30 check valve and strainer employed, being partly in side elevation and partly in section;

Figure 6 is a view similar to Figure 3 but the 35 vanes thereof being disposed at the opposite angle;

Figure 7 is a section taken on the line 7—7 of 40 Figure 6;

Figure 8 is a central, longitudinal sectional view 45 through a modified form of pump;

Figure 9 is a section taken on the line 9—9 50 of Figure 8, and

Figure 10 is a sectional view taken on the line 55 10—10 of Figure 9.

Referring specifically to the drawings where- 55 in like reference characters designate like or corresponding parts throughout the different views, and first to the form of Figs. 1 to 7, 1 designates the pump casing having a removable cover 2 bolted at 2' to one side thereof, which casing encloses an impeller 3 between liners 4 and 50

5. Said liners 4 and 5 have annular, inwardly 55 extending portions 6 and 7 enclosing the impeller and provided with raceways 6' and 7' communi- cating with a common inlet 8, and a common radial outlet 9. Said raceways are blocked or

sealed off between the inlet and outlet by a solid portion 10 of said portions 6 and 7.

Said impeller or rotor 3 is mounted on a tapered portion 11 of a shaft 12 and held rigidly in place by a nut 13 screwed to the shaft. In turn, shaft 12 is mounted on double row ball bearing devices 14 and 15 and sealed by rotary shaft seals 16 and 17 against seats 18 and 19 through the agency of expansive springs 20 and 21 surrounding the shaft. Adjusting nuts 22 and 23 maintain the impeller 3 in proper spaced relation with respect to the liners 4 and 5 to prevent actual metal to metal contact and its undue wear. A spring washer 24 between bearing device 14 and nut 15 22 permits of shaft expansions and contractions. The mounting parts for said shaft are disposed within tubular extensions 1^a and 2^a of the casing and cover and lubricant is supplied to the shaft and other working parts, preferably to maintain 20 a bath, by introduction through openings normally covered by screw plugs 1^b and 2^b.

Specifically, the impeller rotor 3 is of the double cone, triangular or wedge shape at the periphery as shown and intimately contacts with walls of 25 the portions 6 and 7 inwardly of the raceways. The impeller vanes are on opposite sides of rotor 3, extending generally parallel to shaft 12 and designated 27. Said vanes 27 slant in the direction of rotation to the extent of 45° and the faces 30 thereof are also 45° to a line perpendicular to the shaft 12. The base walls of the raceways 6 and 7 are preferably semi-circular and the spaces between adjacent blades or vanes 27 have their base walls substantially semi-circular but 35 preferably flattened slightly at 27'. These vanes, raceways and spaces are designed substantially as described so as to cause the fluid to describe a path of travel approaching a helical or spiral path in the impeller channels or spaces and the 40 raceways, the object being to cause the fluid ahead to dip or return back into the impeller vanes and receive a plurality of impulses to increase the pressure head.

The impeller has grooves 25 engaged by sealing rings or packing 26 of the liners 4 and 5 to prevent radial leakage or inward seepage of fluid.

Said blades 27 preferably have their backs more pronouncedly tapered than their fronts to prevent the formation of eddies and the curved base 50 walls of the spaces or channels between the vanes 27 also prevent the formation of eddies.

In pumping a mixture of air and water, it is preferable to connect an air inlet to only one side or one raceway near the inlet so that the 55 impeller may at all times be water sealed and prevented also from becoming air bound. As a further precaution, an air separating chamber 29 is provided in the outlet 9. This chamber 29 has its wall round with its axis parallel to the axis of shaft 12 and hence it causes the water to form a whirlpool in which a portion of the water will be returned to the vanes 27 to perfect and maintain a water seal while pumping a mixture of water and air. The water in 60 said chamber 29 revolves in the opposite direction to the impeller and thus releases the air at the outlet and a portion of the water is returned to the impeller 3 to displace the air which may have remained between the blades 27.

To compensate for corrosion, erosion and wear, the raceways 4 and 5 are interchangeable and renewable. They are also adjustable for wear 65 independently of the impeller and while the pump is in operation. This adjustment is accomplished 70 by removing screw plugs 30 and adjusting screw

studs 31 by means of a screw driver engaged with key-ways or kerfs 31' thereof. Adjustment of the impeller is effected by relative adjustment of the nuts 22 and 23.

It will be apparent that arrangement of the impeller channels on an angle to a perpendicular line, usually but not necessarily a 45° angle, and raceways to match this angle causes the fluid to be acted upon by centrifugal and tangential forces, the centrifugal force causing the fluid to follow 10 the curved channels and raceways to return the fluid to the blades at the point nearest the axis to receive additional impulses, the inclination of any matter moving in a circle being to fly radially from the center of rotation to the extreme point 15 of the periphery. The fluid is encased and trapped in the channels of the rotor 3 and the raceways 6' and 7' and the resultant forces cause the fluid to be deflected at right angles and downwardly to be returned to the impeller blades 27 where the 20 blades give it added impetus and a succession of such impetuses assists in the two forces mentioned in creating a growing pressure head as the liquid again and again receives kinetic energy from the impeller 3. This efficient action of the impeller is due to a large extent to the tapered impeller with its tapered channels, blades inclined in the direction of rotation, raceways on an angle to match the channels of the tapered impeller to cause the fluid to be acted upon by centrifugal 25 force at the point most remote from the axis of rotation and because the centrifugal force is greatest at this point, the fluid is deflected at right angles and downwardly towards the axis at a point where centrifugal force is not so great 30 returning the fluid to the blades to receive a series of impulses as outlined. The helical or spiral path taken by the fluid results in the fluid returning to the impeller blades at a point farther 35 ahead in the direction of rotation, when it would again receive kinetic energy by the action of the impelling vanes.

The efficiency of the pump is materially increased by the balanced wedge type of the impeller.

Various changes may be resorted to within the spirit and scope of the invention, for instance to dispose the blades or vanes 27 and the channels at angles greater or less than that set forth.

I may also dispose the blades or vanes of the 50 impeller as designated 27' in Figs. 6 and 7 at the opposite angles to those described so that the pump will operate in the reverse direction to that described, the other pump parts corresponding to such reversal.

As shown in Figs. 2 and 5, I may employ a novel combined check valve and strainer combination at the intake or suction end of the pump to keep the water from falling back into the well or source of supply and to protect the impeller and parts 60 from coarse sand and other particles. This device has a casing 32 having an inlet at 33 in line with a removable, tubular screen 34, held in place by a screw plug 35 in one end of casing 32. A pipe 36 connects casing 32 to inlet 8 of the 65 pump, such pipe communicating with a chamber 37 within the casing which communicates with inlet 33 and the screen chamber through a valve seat 38. Said valve seat is normally covered by a check valve 39, removably secured to a stem 70 by nuts 40 and washers 41, the upper end of the stem being slidably telescoped in a depending tube 42 of a removable screw closure or plug 43 for an opening of casing 32 through which the 75 valve and valve seat are applicable and removable.

able. Strainer or screen 34 is removable for cleaning.

Instead of the vanes 27, raceways and channels being provided on two sides of an impeller, they may be provided on one side only, as in the form of Figs. 8, 9, and 10. Specifically, there are two raceways and two sets of blades, the outlet of one raceway being connected to the inlet of the next one to form a two-stage pump. In this form, a casing 44 is used having an inlet 45 and outlet 46. The combined check valve and strainer of Figs. 2 and 5 may be connected to inlet 45 if desired. On one side of casing 44 is a side plate 46 removably bolted in place at 47. Within the casing, an impeller 48 is disposed being mounted on a shaft 49 in the same manner in which impeller 3 is mounted on shaft 12, and said shaft 49 in casing 44 and side plate 46 being mounted in the identical manner in which the aforesaid shaft 12 is mounted. Casing 44 has an interior fluid raceway 50 which is semicircular in cross section and extends more than 360° around the casing, thus being spiral or substantially so. Co-acting with such raceway 50 are vanes 51 and channels or spaces 52, identical in structure and arrangement to the vanes 27 and channels or spaces between them, being however, arranged in a path more than 360° so as to correspond with the raceway 50. Raceway 50 discharges at 53 into the outlet 46. By reason of the construction last described, the impeller 48 is impelled by the fluid almost two revolutions before being discharged so as to increase the pressure head. If desired, the blades or vanes 27, 27', and 51, instead of being integral with the parts carrying them, may be initially separate and welded in place. These separate blades or vanes may be made of very thin sheet metal. Such thin

blades increase the efficiency and pressure of the pump.

I claim as my invention:

A pump of the class described having a casing open at one side provided with an annular wall, a side wall and an outlet chamber extending from the side wall to the open side and outwardly from the annular wall, said chamber having its inner wall curved about an axis substantially parallel to the longitudinal axis of the casing, a shaft journalled longitudinally in said casing, a peripherally wedge-shaped impeller on said shaft, liners disposed one on each side of said impeller, each inclined face of said impeller having channels, blades in said channels inclined in the direction of rotation and disposed at an angle to the axis of the impeller, said liners having portions jointly surrounding the periphery of the impeller and provided with raceways opposite the respective channels and communicating through said portions with said outlet chamber, and a closure at said open side of the casing abutting one of said liners and secured to the casing, said side wall and closure having tubular outward extensions disposed about said shaft provided with interior shoulders, seat members for said shaft located in said extensions and abutting said shoulders, seal devices about the shaft engaging said impeller and said seat members, expansive springs about the shaft engaging said impeller and said seal devices, said impeller having a tapered fit on said shaft with the taper flaring in a direction away from said closure, and screw elements on said closure operable from the exterior of the pump and against one of the liners to move the same and adjacent parts to take up wear.

JAMES O. McMILLAN.
